UNITED STATES PATENT OFFICE

165,713

SWEATER

Barnett D. Gordon, Brookline, Mass.

Application July 31, 1951, Serial No. 16,093

Term of patent 14 years

(Cl. D3—4)

To all whom it may concern:

Be it known that I, Barnett D. Gordon, a citizen of the United States, residing at Brookline, in the county of Norfolk and State of Massachusetts, have invented a new, original, and Ornamental Design for a Sweater, of which the following is a specification, reference being had to the accompanying drawings, forming part thereof.

The figure of the drawing is a front elevation of a sweater showing my new design in full lines, the back portion of the garment being of conventional appearance.

I claim:

The ornamental design for a sweater, as shown and described.

BARNETT D. GORDON.
